(57) **CLAIM**

The ornamental design for the flying disk game target stand, as shown and described.

DESCRIPTION

The present application is related to commonly assigned U.S. Design patent application Ser. No. 29/635,364 filed 30 Jan. 2018.

FIG. 1 is a front left perspective view of a flying disk game target stand showing our new design.

FIG. 2 is a front view of the flying disk game target stand. FIG. 3 is a back view of the flying disk game target stand. FIG. 4 is a right side view of the flying disk game target stand.

FIG. 5 is a left side view of the flying disk game target stand. FIG. 6 is a top view of the flying disk game target stand; and, FIG. 7 is a bottom view of the flying disk game target stand. The broken lines showing rocket target game accessories depict environment and form no part of the claimed design.
